REFRIGERATING APPARATUS

Alex A. McCormack, Dayton, Ohio, assignor to
General Motors Corporation, Dayton, Ohio, a
corporation of Delaware

Application March 26, 1941, Serial No. 385,294

5 Claims. (Cl. 62—115)

This invention relates to refrigerating apparatus and more particularly to an improved compressor unloading means.

It is an object of this invention to provide a simple centrifugal unloader which may be added to a standard rotary compressor without rearranging any of the compressor parts.

Another object of this invention is to provide a centrifugal unloader which may be fully tested prior to mounting on the compressor.

A further object is to provide an unloader which may be removed from a compressor and replaced by means of an ordinary cap screw when it is desired to operate the compressor without an unloader.

Further objects and advantages of the present invention will be apparent from the following description, reference being had to the accompanying drawings, wherein a preferred form of the present invention is clearly shown.

In the drawings:

Fig. 1 is a sectional view partly diagrammatic showing my invention applied to a compressor;

Fig. 2 is an enlarged view of the unloader unit;

Fig. 3 is a sectional view taken on the line 3—3 of Fig. 2; and

Fig. 4 shows a refrigerating system equipped with an unloader constructed in accordance with my invention.

It is recognized that it is old to use centrifugal unloaders and that many patents have been granted on various types of unloaders. However, the prior art centrifugal unloaders have not been fully satisfactory for various reasons.

For purpose of illustration, I have shown my invention applied to a four-vane rotary compressor unit. Reference numeral 10 designates generally a sealed motor-compressor-condenser unit connected in refrigerant flow relationship with an evaporator 28. The unit 10 comprises a conventional motor having a stator 12 and a rotor 14. The rotor 14 is mounted on a shaft 16 which operates a conventional four-vane rotor 18. The rotor 18 operates within a conventional compressor cylinder 20. The shaft 16 is journaled in a main bearing 22 which is formed integrally with the main supporting frame 24. The compressor is provided with an inlet 26 connected to the vapor line 30 which communicates with the refrigerant evaporator 28. The flow of refrigerant to the evaporator 28 is controlled by a conventional fixed restrictor 29 provided in the liquid line 31. A fan 33 circulates air over the evaporator 28. The compressor is provided with a conventional compressor outlet (not shown)

which discharges the compressed gas into the motor-compressor compartment 32 in accordance with standard practice. The compressed gas discharged into the chamber 32 is condensed when coming in contact with the water coils 34. Water is supplied to the coil 34 through the water feed line 36 and leaves through the line 38. The flow of water through the coil 34 is controlled by a conventional type of pressure operated valve 40 arranged in the line 38 and provided with line 42 which connects the pressure chamber of the valve 40 with the chamber 32 in accordance with well-known practice.

The compressor chamber 46 contains a supply of lubricant 44 which is subjected to the high side pressure. Lubricant is supplied to the main compressor bearing through the bore 48 provided in the lower end of the main shaft 16. The bore 48 communicates with a radial passage 50 which 15 supplies lubricant to the lower end of the bearing 22 and to the upper end of the bearing via the passage 52 provided in the bearing itself. The central portion of the main bearing 22 is recessed as shown at 54. A passage 56 connects the recess 54 with the main compressor inlet. A shaft seal 57 which may be of any conventional construction prevents the escape of lubricant from the upper end of the main shaft bearing 22, as shown in Fig. 1. It is apparent, therefore, that 20 the pressure within the chamber 54 is substantially equal to the suction pressure or the low side pressure. Inasmuch as the main body of lubricant 44 is subjected to the discharge pressure or the high side pressure, there is a definite 25 tendency for the lubricant supplied to the end portions of the main bearing 22 to flow towards the low pressure cavity 54 at the center of the bearing. Thus, the difference in pressure between the high and the low sides of the system 30 forces the lubricant to the bearing surfaces.

A very simple centrifugal unloader may be added in a compressor of this type merely by boring out the upper end of the shaft 16 as shown at 60 and mounting a centrifugally operated valve unit 62 in the upper end of the bore 60. The lower end of the bore 60 communicates with a radial passage 64 which in turn communicates with the low pressure compression chamber through the recess 54 and the passage 56. The 35 centrifugal unloading unit 62 comprises a cap screw 66 having a central passage 68 extending from the lower end of the screw to the radial passage 70 adjacent the head 74 (see Fig. 2). A flattened surface 72 is provided adjacent the outer 40 end of the radial passage 70 and serves as a

valve seat, as shown in Fig. 3. A washer 76 is secured to the upper end of the bolt. The washer 76 carries a pivot pin 78 on which is pivotally mounted a bell crank 80. The arm 82 of the bell crank 80 is larger and heavier than the arm 83. The arm 83 carries a neoprene valve member 84 which cooperates with the port or passage 70. A spring 86 biases the bell crank 80 into valve opening position so that in the absence of any centrifugal force opposing the force of the spring 86, the valve 84 remains in the open position, whereby the high pressure chamber 32 communicates with the compression chamber through the passages 70, 80, 64, 54 and 56.

Upon energization of the compressor motor, the heavier end 82 of the bell crank 80 tends to swing away from the center of rotation of the shaft 16 and overcomes the force of the spring 86 so as to automatically close the valve 84. As shown in Figs. 2 and 3, the one end 90 of the spring 86 rests against the outer periphery of the disk 76 and the other end 92 engages the aperture 94 in the bell crank 80. The cap screw 66 also serves to fasten the motor-rotor 14 to the shaft 16. A pair of washers 96 and 98 have been provided as shown in Figs. 1 and 2. The large washer 96 engages the upper surface of the motor-rotor 14. The washer 98 is a conventional lock-nut washer which serves to prevent the cap screw 66 from becoming loose.

One big advantage of the unloader unit 62 is that it may be tested prior to mounting in the compressor unit. By mounting the unit 62 on a testing device, the speed at which the unloading valve opens may be tested and, if necessary, adjusted. Furthermore, the valve may also be tested so as to see whether or not the valve adequately seals the unloading passage.

By virtue of the above construction, a very simple unloading unit not only serves as an unloader but also serves to fasten the motor-rotor to the main shaft 16.

While the form of embodiment of the invention as herein disclosed, constitutes a preferred form, it is to be understood that other forms might be adopted, all coming within the scope of the claims which follow.

What is claimed is as follows:

1. In a refrigerating system having a high pressure portion and a low pressure portion, a compressor comprising a shaft, means for supplying lubricant to said shaft including a lubricant passage having one portion in communication with the low pressure portion of said system, a cen-

trifugal unloader carried by said shaft having means for equalizing the pressure between the high pressure portion of said system and the low pressure portion of said system, said unloader utilizing said one portion of said lubricant passage as an unloading passage.

2. Refrigerating apparatus comprising a casing, a compressor within said casing, a compressor operating shaft having a compressor unloading passage provided therein, a valve assembly removably mounted on said shaft as a unit and having a valve port communicating with said passage, said unit including valve means controlling the flow of fluid through said port and means responsive to the speed of said shaft for operating said valve means.

3. A centrifugal unloading device for a compressor unit having an unloading passage formed in the compressor operating shaft comprising in combination, means removably secured to said shaft as a unit including a member having a passage communicating with said unloading passage, a valve carried by said member for opening and closing the passage in said member, and means carried by said member responsive to the speed of said compressor for opening and closing said valve.

4. In combination, a rotatable shaft having a fluid passage therein, a fluid flow control unit removably secured to said shaft and having a valve port communicating with said passage, said unit including valve means controlling the flow of fluid through said port and means responsive to the speed of said shaft for operating said valve means.

5. In combination, a compressor, a compressor casing forming a lubricant sump, an inlet port for said compressor, an outlet port for said compressor through which compressed gas is discharged into said casing, means for supplying lubricant from said sump to said compressor comprising a lubricant passage, means whereby one portion of said passage communicates with said inlet port, said shaft having an axial bore communicating with one portion of said lubricant passage, a valve assembly removably secured to said shaft as a unit, said assembly having a passage communicating with said bore and with the interior of said casing and having means responsive to changes in the speed of said shaft for closing said passage at high speeds and opening said passage at low speeds.

ALEX A. McCORMACK.
